UNITED STATES PATENT OFFICE.

HENRY W. BERTRAM, OF FRANKFORT, INDIANA, ASSIGNOR TO McDougall Company,
OF FRANKFORT, INDIANA, A CORPORATION OF INDIANA.

KITCHEN-CABINET.

1,113,928.

Specification of Letters Patent. Patented Oct. 13, 1914.

Application filed July 12, 1913. Serial No. 778,657.

To all whom it may concern:

Be it known that I, HENRY W. BERTRAM, a citizen of the United States, residing at Frankfort, in the county of Clinton and State of Indiana, have invented a new and useful Kitchen-Cabinet, of which the following is a specification.

At the present time marketable "kitchen cabinets" have general characteristics which are considered necessary. They must have a lower cabinet base comprising drawers and a cupboard, surmounted by a work-table which is generally outwardly movable to increase its available working face. Above this work table there is a cabinet structure within which are arranged various receptacles for the storage of materials, dishes, etc. The lower portion of the surmounting cabinet immediately above the work table, should be closable and it has been generally customary to provide swinging doors, hinged at the sides of the surmounting cabinet, for this purpose but preliminary to the movement of such doors it is essential that the work table be practically clear of all material. This necessity has resulted in considerable annoyance and objection and it has heretofore been proposed to close this portion of the cabinet by a horizontally moving flexible curtain but such an arrangement is very objectionable because of the necessity of provision of grooved tracks or ways in the floor of the compartment.

The object of my present invention is, therefore to provide a roller curtain closure for the lower compartment of the surmounting cabinet portion of the kitchen cabinet of such character that it will, when open, present a free and level floor space free from grooves or depressions which would afford lodgment for dust, dirt, etc.

The accompanying drawing illustrates my invention.

Figure 1 is a perspective view of my improved structure; Fig. 2 a fragmentary vertical section; Fig. 3 a still more fragmentary section of some of the parts shown in Fig. 2; Fig. 4 a fragmentary front elevation of the lock rail and strike rail; Fig. 5 a fragmentary section on line 5—5 of Fig. 3.

In the drawings 1 indicates the lower cabinet structure of the complete kitchen cabinet and to the rear upper corners of this structure are screwed the brackets 2, 2 which

receive the sliding top 3 and support the upper cabinet structure 4, said upper cabinet structure comprising the side-boards 5, back 6 and floor 7. In my structure the floor 7 is formed with an internal horizontal chamber 8 which at its rear end is supplemented by a vertical chamber 9 immediately back of the false back 10 which is arranged in the lower part of the compartment 11. Chamber 8 at its front is partially closed by a front rail or bar 12 which at its inner upper corner is inwardly and downwardly beveled as indicated at 13 so as to form an entrance into chamber 8, and at its upper outer corner is provided with a seat 13'. Each side-board 5 at its front is supplemented by a corner post 14 which at its inner corner is rabbeted at 15 and upon the side face of this rabbet is mounted an angle bar 16 which is extended downwardly and rearwardly in chamber 8 and upwardly in chamber 9 so as to form a guide, in the usual manner, for the several sections of a flexible or so-called "roller" curtain 19.

The initial member 19' of curtain 19, is 80 supplemented by a strike bar 20 detachably secured by screws 21. Bar 20, at its inner edge is beveled, as indicated at 23, and the forward edge of bottom 7 is oppositely beveled, as at 22, so that there may be some variation of position of bar 20 while at all times maintaining a close union with the forward upper corner of bottom 7. Bar 20, at its front is provided with a semi-cylindrical rib 20' which seats in seat 13' and insures a proper engagement between the front upper corner of bottom 7 and the rear corner of the bar 20 when the bar is in its lowest position so as to form a continuation of the upper face of bottom 7 and prevent entry of crumbs into the channels 9 and 8. Instead of mounting the lock in the free edge of the flexible curtain as has usually been the custom in desks, etc., where such curtains are used, I provide the bar 20 100 with a "pull" 24 which projects forwardly, as clearly indicated. The upper part of compartment 11 is bridged by the lock bar 30 on the front face of which is mounted a latch 31 provided with the usual catch bar 32 formed for engagement with the "pull" 24.

By this arrangement I have been able to produce a closure for the lower compartment of the upper cabinet of the kitchen 110

cabinet which can be freely opened and closed without interfering with any materials resting upon the work table and yet of such character that no obstruction is offered to the free withdrawal of any materials lying upon the floor of the compartment when the closure is withdrawn from closing position.

The rear end of track 16 is so arranged that, by removing a portion of back 6 and withdrawing screws 21, the curtain 19 may be readily withdrawn to permit ready clearing of channel 8 if necessary.

I claim as my invention:

1. In a kitchen cabinet, the combination with the main body, the work table surmounting the main body, and the superstructure arranged above the work table and having a floored compartment above the work table, of guide-ways arranged at the front corners of said compartment and extending rearwardly beneath the floor of the compartment, a flexible curtain arranged between said guide-ways and projectable beneath the floor of the compartment, and a strike bar having a free upper face and carried by the free edge of said curtain to coöperate with the forward edge of the compartment floor to close the slot between such floor and the curtain and form a continuation of said floor when the curtain is lowered, and a lock arranged in the upper part of the compartment, and a projection carried by the curtain to engage the lock when the curtain is raised to closing position.

2. In a kitchen cabinet, the combination with the main body, the work table surmounting the main body, and the superstructure arranged above the work table and having a floored compartment above the work table, of guide-ways arranged at the front corners of said compartment and extending rearwardly beneath the floor of the compartment, a flexible curtain arranged between said guide-ways and projectable beneath the floor of the compartment, and a bar having a free upper face and carried by the free edge of said curtain to coöperate with the forward edge of the compartment floor to close the slot between such floor and the curtain and form a continuation of said floor when the curtain is lowered.

erate with the forward edge of the compartment floor to close the slot between such floor and the curtain and form a continuation of said floor when the curtain is lowered, said bar and the floor having oppositely inclined adjacent surfaces meeting at their upper corners, and a supporting bar for supporting the forward face of the first mentioned bar when the curtain is lowered.

3. In a kitchen cabinet, the combination with the main body, the work table surmounting the main body, and the superstructure arranged above the work table and having a floored compartment above the work table, of guide-ways arranged at the front corners of said compartment and extending rearwardly beneath the floor of the compartment, a flexible curtain arranged between said guide-ways and projectable beneath the floor of the compartment, and a bar having a free upper face and carried by the free edge of said curtain to coöperate with the forward edge of the compartment floor to close the slot between such floor and the curtain and form a continuation of said floor when the curtain is lowered.

4. In a kitchen cabinet, a floored compartment, guide-ways arranged at the front corners of said compartment and extending rearwardly beneath the floor of the compartment, a flexible curtain arranged between said guide-ways and projectable beneath the floor of the compartment, and a bar having a free upper face and carried by the free edge of said curtain to coöperate with the forward edge of the compartment floor to close the slot between such floor and the curtain and form a continuation of said floor when the curtain is lowered.

In witness whereof, I have hereunto set my hand at Frankfort, Indiana, this 9th day of July, A. D. one thousand nine hundred and thirteen.

HENRY W. BERTRAM.
